UNITED STATES PATENT OFFICE.

JACOB S. THORN, OF PHILADELPHIA, PENNSYLVANIA.

DESIGN FOR A SHINGLE OR ROOFING-PLATE.

SPECIFICATION forming part of Design No. 18,212, dated March 27, 1888.

Application filed February 27, 1888. Serial No. 265,520. Term of patent 14 years.

To all whom it may concern:

Be it known that I, JACOB S. THORN, of the city and county of Philadelphia, State of Pennsylvania, have invented and produced a new 5 and original Design for Metallic Roofing-Plates or Shingles, of which the following is a specification, reference being had to the accompanying drawings, which form a part thereof, and in which—

10 Figure 1 is a perspective view of my newly-designed roofing-plate, and Fig. 2 a side view of the same, these two views being deemed necessary to fully illustrate my design.

15 My new design consists of a roofing-plate having a thickened lower edge of the peculiar outline shown in the drawings—that is, said lower edge is bounded by two converging and inwardly-curved lines, and a third line running across the center line of the shingle, so as 20 to intersect the curved lines aforesaid—said shingle also having an elongated projection extending along the median line on its upper surface.

25 A is the face or upper visible part of the shingle, having preferably side edges, *a a*, parallel to its median line.

B is the raised or struck-up lower edge of the shingle, bounded by the inwardly-curved

lines *b b* and the intersecting line *b'*, lying across the center line of the shingle. 30

C is the elongated elevated boss, formed, as shown, along the median line of the shingle.

D indicates the upper portion of the visible face of the shingle, which is generally only outlined clearly when coupled with similar shingles, and therefore forms no part of my 35 design. The dotted lines indicate flanges, edges, &c., of the shingle, which are situated outside of its visible face, and may be of any construction without in any way affecting my 40 design.

I claim—

The design for a metallic shingle or roofing-plate herein shown and described, the same 45 consisting of a shingle having a thickened lower edge bounded by two inwardly-curved converging lines, and an intersecting line lying across the center line of the shingle, and having also the elevated elongated projection C 50 extending along the median line of its upper surface.

JACOB S. THORN.
